UNITED STATES PATENT OFFICE.

HARRISON B. WALTER, OF CHICAGO, ILLINOIS, ASSIGNOR, BY MESNE ASSIGNMENTS, TO CONTAINER CORPORATION OF AMERICA, OF CHICAGO, ILLINOIS, A CORPORATION OF DELAWARE.

METHOD OF PACKING DOORS, FRAMES, AND THE LIKE.

Application filed July 26, 1926. Serial No. 124,998.

This invention relates to a novel and improved method for packing doors, sashes, frames and like articles, made usually of wood and of comparatively large size and 5 consists in the matters hereinafter described and more particularly pointed out in the appended claims.

Doors, sashes, frames and like articles of wood made in a factory and shipped to the 10 place of use, are generally crated or packed in wooden crates or frames, which are not only expensive and troublesome to make, but also add greatly to the weight of the package, thereby increasing the cost of shipping. 15 In the modern development of the use of fibre board for shipping-cases, boxes and the like, there has been an attempt to obtain the advantage in packing doors and the like in saving of cost of material and saving of 20 weight to reduce the cost of shipping by the use of fibre board for such packing; but owing to the great variety in sizes required for such packing, the use of fibre board for such purpose has not made much headway.

25 The object of my invention is to provide a method of wrapping and packing articles of the kind and a package to contain the same by means of which it is possible to economically and advantageously use fibre 30 board in packing such articles for shipment, with all the desired saving of cost and weight of material in the package and in the practice of which a minimum number of blanks is required to provide packages to accommodate the necessary great variety in 35 the dimensions of the said articles. The many advantages of the invention will appear more fully as I proceed with my specification.

40 In order to illustrate the method I attach hereto drawings showing the forms of blanks used and the different steps followed in carrying on the improved method of packing. I have illustrated the method in 45 connection with the packing of the ordinary wood doors; but it will be understood that the method is applicable to other articles of the kind.

In the said drawings:

50 Figure 1 is a view representing in perspective two doors, one laid upon the other to represent an assembly of doors to be packed.

Figure 2 is a perspective view representing the doors of Figure 1 as they appear 55 when enclosed by two of the blanks used in carrying out the method.

Figure 3 is a view representing a transverse section through Figure 2 with the thickness and spacing of the parts exaggerated for purposes of illustration. Figure 4 60 is a perspective view representing one end of the package in the next stage of the packing process, in which the ends of the package 65 are provided.

Figure 5 is a view similar to Figure 4 showing the first step of closing the end of the package and

Figure 6 is a like view showing the end 70 of the package finally closed.

Figure 7 is a perspective view showing the completed package with the addition of end and intermediate binders which complete the package ready for shipment.

Figure 8 is a perspective view showing the 75 different elements or blanks which go to form the package.

Figures 9 and 10 are transverse sections through the package similar to Figure 3 80 illustrating the method of folding the main body blanks when the package contains more than two doors, namely six doors in Figure 9 and three doors in Figure 10.

Figures 11 and 12 are edge elevations illustrating the positions occupied by the main 85 blanks of the package in the case of doors of different lengths.

In carrying out the improved method there are provided and sent to the packer four pieces or blanks:—two main blanks 13, 90 13 (see Figure 8) and two end or cap blanks 14, 14,—one for each end of the package. These are cut and sent to the shipper flat. In Figure 8 they are shown in the form which they are made to assume in the 95 hands of the packer, who makes the package in the manner now to be described; but it is to be understood that when sent to him they are flat and without any bends or creases, except the score mark hereafter 100 mentioned in the blanks 14.

In making the package, the packer takes each of the two main blanks 13, 13 and first, knowing the width of the door, forms a 105 crease 16 (see Figure 8) running the length of the blank to provide a panel 17 substan-

tially of the width of the doors constituting the package. Next he forms a crease 18 running parallel to the crease 16, providing between the crease lines 16 and 18 a narrow panel 19 which is equal to the thickness or depth of the package to be made. This depends upon the number of doors to be included in the package,—in the case assumed and shown in Figure 2, two doors. This leaves a panel 20 beyond the crease line 18. These crease lines may be formed in any convenient way, but are readily and quickly provided by means of a hand creasing device shown in an application executed of even date herewith, which includes a gauge by means of which the crease lines may be properly spaced and formed in rapid succession.

Having creased each of the main blanks 13 in the manner described, the assembly of doors is laid upon the main panel 17 of the one main blank 13 (see Figure 3) and the panel 19 thereof is brought up along the edge of the two doors and the panel 20 is laid upon the top side of the top door. The other or second main blank 13 is similarly applied. The panel 17 of the second blank is laid upon the top of the package and over the panel 20 of the first blank 13; its panel 19 is brought down against the other edge of the door package; and its panel 20 is inserted between the bottom of the door package and above the panel 17 of the first blank. This produces the result as pictured in section in Figure 3 and in perspective in Figure 2, wherein the package of two doors is completely enclosed except at the ends. A metal strap or other binder 21 is then bound and drawn forcibly about the package intermediate its ends and the ends of the strap are sealed together in any familiar manner.

The package of doors as shown in Figures 2 and also 11 and 12 extends somewhat beyond the ends of these main blanks. Upon this point it is simply necessary to note that the general run of doors of the kind vary in length from six to seven feet and that by providing three different lengths of the main blanks 13, one for a short length series, one for an intermediate length series, and one for the greatest length series, the blanks 13 will extend the full length of a door or will extend nearly that length as shown in Figures 2, 11 and 12, so that substantially the length of the door package is covered by the length of the main blanks.

The blank for the cap or end closure of the package is a strip 14 adapted to be wrapped transversely about the end margin of the package and overlapped upon itself as shown in Figure 4. It is comparatively narrow and has a score mark 14* running lengthwise of the strip midway of its shorter dimension. The blank 14 is applied with

a part 14^a of its shorter dimension overlapping the ends of the main blanks 13 and a part 14^b projecting beyond the ends of the doors. A strap or other binder 22 is then bound around the package adjacent the ends of the doors and sealed in any convenient manner as in the case of the middle binder 12. The blank 14 is then slit along the fold lines 15 beyond the ends of the doors, as illustrated in Figure 5. The severed parts 14^b of the blank 14 are then folded down in overlapping relation against the ends of the doors and fixed in place by one or more tacks or nails as illustrated in Figure 6. The caps having been attached to both ends of the package in the manner described, the package is complete and ready for shipment.

As the doors vary in length, so also they vary in width. Also the depth or thickness of the package varies with the number of doors to be included in the package. Generally the number of doors in a package does not exceed six. I have found that three widths of the main blanks will accommodate all the regular widths of doors. And the blanks for any width of door which it is designed to accommodate will be made to properly enclose the package no matter how many doors are included, the width of the panel 20 decreasing as the number of doors in the package increases. Thus in Figure 3 the panel 20 is quite wide, whereas in Figure 9 said panel indicated at 20^a is quite narrow, the package including six doors as against the two doors in Figure 3. In Figure 10 there is shown a package of three doors of greater width. The main blanks in all cases are always wide enough to provide a panel 20 of sufficient width to overlap one margin of the package and to overlies so as to be gripped by the margin of the main panel 17 of the other blank 13.

The advantages, the simplicity and the speed of manipulation of the method herein described for packing doors and the like for shipment, will be manifest to those familiar with the art. Blanks provided for a minimum number of series of doors of different lengths and widths are required to pack all doors or the like of the usual dimensions and, as hereinbefore pointed out, I have found that three different sizes of the main blanks will accommodate in the case of doors all the varied dimensions of standard doors generally manufactured. Where the dimensions of the articles to be packed do not vary so widely as in the case of doors, a lesser number of different sized blanks is required, whereas in case said dimensions vary even more widely, a greater number of different dimension blanks may be needed. As stated, however, blanks of three different dimensions will generally in the method described meet most requirements.

No claim herein is made to the package

produced by the method, said package being claimed in a separate application executed of even date herewith.

I claim as my invention:—

- 5 1. The method of packing doors, and the like, which consists in providing two main blanks, each of a length approximating the length of the doors to be included in a package and of a width exceeding the combined width of the widest door of a series and the 10 depth of a package to contain the maximum number of doors of that series to be included, in creasing each blank to provide a plurality of panels running the length of 15 the blank, one panel of the width of the doors to be included in a package, one, of the depth of the package, and a third panel to close one margin of the package, in wrapping said blanks about the package of doors 20 in overlapped relation, in then closing each end of the package by a strip which is wrapped about the said end and overlapped upon itself, said strip being overlapped on one side on the end of the main blanks and 25 on the other side extending beyond the end of the package, and in then slitting said strip beyond the doors, folding the severed parts of said strip into overlapping relation against the ends of the doors and securing 30 them in such overlapped relation against the ends of the package of doors.

2. The method of packing doors, and the like, which consists in providing two main

blanks, each of a length approximating the length of the doors to be included in a package and of a width exceeding the combined width of the widest door of a series and the 35 depth of a package to contain the maximum number of doors of that series to be included, in creasing each blank to provide a plurality of panels running the length of the blank, one panel of the width of the doors to be included in a package, one, of the depth of the package, and a third panel to close on a margin of the package, in 40 wrapping said blanks about the package of doors in overlapped relation, in applying a binding member about said blanks to secure them in place upon the package, in then closing each end of the package by a strip which is wrapped about the said end and 45 overlapped upon itself, said strip being overlapped on one side on the end of the main blanks and on the other side extending beyond the end of the package, in applying a binder about said strip to secure it in place on the package, and in then slitting said strip beyond the doors, folding the severed parts of said strip into overlapping relation 50 against the ends of the doors and securing them in such overlapped relation against the ends of the package of doors.

In testimony that I claim the foregoing as my invention, I affix my signature this 17 day of July, A. D. 1926.

HARRISON B. WALTER.
